(57) **CLAIM**

The ornamental design for footwear with integrated sensor, as shown and described.

DESCRIPTION

FIG. 1 is a perspective view of the invention, which features a partial cutaway view of an article of footwear in phantom lines.

FIG. 2 is a side view of the invention, which features an article of footwear in phantom lines.

FIG. 3 is a perspective view of the invention; and,
FIG. 4 is a side view of the invention.

The phantom lines shown in FIGS. 1-2 are illustrative purposes only, depicting environmental structure that forms no part of the claimed design.
